(57) **CLAIM**

The ornamental design for a construction set element, as shown and described.

DESCRIPTION

FIG. 1 is a top perspective view of a construction set element showing the new design;

FIG. 2 is a top plan view thereof;

FIG. 3 is a bottom plan view thereof;

FIG. 4 is a front elevational view thereof;

FIG. 5 is a rear elevational view thereof, from the position of line 5-5 in FIG. 2;

FIG. 6 is a side elevational view thereof, from the position of line 6-6 in FIG. 2; and,

FIG. 7 is an opposite side elevational view thereof, from the position of line 7-7 in FIG. 2.

(Continued)

The evenly spaced broken lines and unshaded areas are included to illustrate parts of the article's appearance that form no part of the claimed design.

The long and short broken lines define the bounds of the claimed design and form no part thereof.

1 Claim, 7 Drawing Sheets
